UNITED STATES PATENT OFFICE.

WALTER S. LANG, OF SEWICKLEY, PENNSYLVANIA.

COMBINATION BROOM PRESS AND NAILER.

1,101,637.

Specification of Letters Patent. Patented June 30, 1914.

Application filed January 25, 1911. Serial No. 604,589.

To all whom it may concern:

Be it known that I, WALTER S. LANG, of Sewickley, Allegheny county, Pennsylvania, have invented a new and useful Combination Broom Press and Nailer, of which the following is a full, clear, and exact description, reference being had to the accompanying drawings, forming part of this specification, in which—

10 Figure 1 is a side elevation of a preferred form of machine embodying my invention; Fig. 1^a is a side view showing a broom formed and nailed by my improved machine; Fig. 2 is a front elevation thereof; 15 Fig. 3 is a plan view on a larger scale of the nail sorter and feeder; Fig. 4 is a section on the line IV—IV of Fig. 3; Fig. 5 is a view partly in side elevation and partly in vertical section showing portions of the machine; Fig. 6 is a perspective view of the stationary anvil; Fig. 7 is a perspective view of the lower movable anvil; Fig. 8 is a plan view, and Fig. 9 a vertical section of a portion of the nail trough; and Figs. 10 and 11 20 are perspective views of cam lugs herein-after more fully described.

My invention has relation to broom-making machinery, and more particularly to a combined machine for pressing the brooms 30 with the hoods and bands therefor into final shape and for nailing the hoods and bands to the brooms.

The object of my invention is to provide a machine of this character which will be 35 simple and effective in its operation, and which will enable the work to be done rapidly and accurately and at a relatively low cost.

The nature of my invention will be best 40 understood by reference to the accompanying drawings, in which I have shown the preferred embodiment thereof, and which will now be described, it being premised, however, that various changes may be made 45 in the details of construction and arrangement of the several parts without departing from the spirit and scope of my invention as defined in the appended claim.

In these drawings, the numeral 2 designates 50 the frame of the machine, which may be of any suitable character; 3 designates the main driving shaft, which is mounted in suitable bearings 4 at the upper portion of the frame, and which may be driven in any 55 suitable way as by a belt-pulley 5. The shaft 3 carries a pinion 6, which meshes with

a spur gear wheel 7 on a shaft 8. The wheel 7 is loosely mounted on the shaft 8, and has a clutch hub 9, which is adapted for engagement with an endwise movable 60 clutch member 10.

11 is a spring having a tendency to force the clutch member 10 into engagement with the clutch hub 9. The clutch member 10 has an annular groove therein, formed with a 65 cam wall 12.

13 is a clutch releasing rod, having a handle portion 14. This rod is arranged to be projected by a spring 15 into engagement with the groove of the clutch member. 70

Mounted on the shaft 8 is an eccentric 16, to the strap 17 of which is connected an adjustable plunger or pitman 18, whose lower end is pivoted at 19 within a tapered recess 20 of a hammer or driving block 21. This 75 hammer or drive block is arranged to reciprocate vertically in the guides 22. The hammer or drive block carries a plurality of drivers 23.

24 is a fixed anvil, which is secured in the 80 frame below the hammer or drive block, and which is formed with a plurality of vertical perforations 25 to permit the drivers 23 to pass therethrough.

26 is the lower movable anvil or press 85 head, which is mounted on the reciprocating head 27. This head is arranged to move vertically in the guides 28. It is actuated by the toggle members 29 and 30, the member 29 being pivoted at 31 at its upper end with- 90 in a tapering recess 32 of the head; the two members being pivotally connected at 33, and the lower member being connected to a rock shaft 34 mounted in the lower portion of the machine, and also having secured 95 thereto a foot lever or treadle 35.

36 is a stop for the foot lever or treadle.

The two anvils or press blocks 24 and 26 are each formed with a cavity 37 in its working face, these cavities being of the proper 100 form to shape and compress the broom when it is placed therein, as will be clearly seen by reference to Figs. 1 and 5.

My invention also provides mechanism for automatically feeding the nails to the driver 105 in position to be driven, and this part of my invention will now be described.

38 is a nail hopper or receptacle, which is pivotally supported in bearings 39 carried by rearwardly projecting arms 40 at the 110 upper portion of the frame. This hopper is arranged to tilt on its bearings, as indicated

in Fig. 1. The bottom of the hopper is provided with a plurality of parallel slots 41, which are of such width that the shanks of the nails can fall therethrough so that the 5 nails will be suspended by their heads and will hang through these slots in the manner shown in Fig. 1. The hopper receptacle is provided with the longitudinal barrier 42, whose lower edge is separated from the bottom 10 of the hopper a sufficient distance, as indicated at 43, to permit the heads of those nails which are properly suspended through the slots to pass thereunder, but which will prevent the passage of nails which do not 15 assume such position.

44 designates a partition member, which acts as a separator between nails of different sizes. The front edge of the bottom of the nail hopper or receptacle in front of the barrier 42, is provided with a series of slots 20 or recesses 45, one of which is located between each two adjacent slots 41.

46 is an endwise movable bar, which abuts against the front edge of the bottom portion of the hopper or receptacle in the manner shown in Figs. 3 and 4, this bar having therein a plurality of short slots 47, which correspond to and register with the slots 41. When the nail hopper or receptacle is tipped 25 to a position in which its bottom is inclined downwardly and forwardly, the nails which are suspended in the slots will slide down these slots, and the foremost nail in each slot will pass into the adjacent short slot 47 in the bar 46, and will be retained in this 30 position until said bar is moved endwise to bring the nails opposite the slots or recesses 45. These slots or recesses 45 are sufficiently large to permit the heads of the 35 nails to drop therethrough. When the nails are thus released from the bar 46 they fall end first with their points downward into a receiving trough 48, a portion of which is shown in detail in Figs. 8 and 9. This 40 trough is mounted in supports 40^a, which depend from the frame arms 40. The trough is provided with a plurality of tapered vertical openings 49 extending therethrough and communicating each at its 45 lower end with a nail feed tube 50. The nail feed tubes converge at their lower ends directly above a nail-carrier slide 51, best 50 shown in Fig. 5. This slide 51 is mounted to reciprocate horizontally on supports 52 of the frame, and to be carried directly 55 under the nail drivers 23. It is provided with a series of vertical nail receiving apertures 53, which are arranged to correspond to the arrangement of the nails to be driven 60 through the hood and reinforcing band of the broom, and also exactly corresponding with the arrangement of the drivers 23.

54 is a plate on the bottom of the slide 51, and having therethrough a plurality of 65 openings 55 which are normally out of reg-

ister with the openings 53, but are arranged to be brought into register with said openings, with which they correspond in number and disposition. The plate 54 is normally held in the non-registering position shown 70 in Fig. 5, by the action of a spring 56. When the slide 51 is moved forwardly underneath the driver 23, the front edge of the plate 54 will contact with the stop wall 57, and will be moved backwardly against 75 the action of the spring 56 to thereby bring its openings 55 into register with the openings 53.

For the purpose of automatically operating the nail assorter and distributor 38, it 80 has an upwardly projecting arm 58, which is connected by a link 59 with the arm 60 of a bell crank lever 61, which is sleeved on the shaft 3, and which has its other arm 62 connected by a link 63 with the eccentric 85 strap 17. The connections are such that at the proper time the receptacle 38 will be tilted from the position shown in Fig. 1 into a position in which its bottom is inclined downwardly and forwardly so that it 90 will deliver one set of nails. It is then moved back to the position shown in Fig. 1.

The slide 51 may be operated in various ways. It is shown as having a depending arm 64, to which is connected a link 65. 95 This link is in turn connected to a sleeve 70 mounted on the shaft 71 having a counterweighted arm 72. The sleeve 70 has another arm 73, which is connected by link 74 with hand lever 75 pivoted to the frame at 76. 100

The operation is as follows:—The broom with the hood and band thereon are placed between the anvils or press blocks 24 and 26, the lower anvil or press block being at this time in its down position, as shown in 105 Fig. 5. The operator then places his foot on the foot lever or treadle 35, and forces the anvil or press block 26 upwardly, thereby pressing and giving the final shape to the broom, and firmly clamping the hood 110 and band thereto. Owing to the toggle action of the actuating connections for the lower end of the press block, a very powerful pressing action may be obtained. The operator then pulls the clutch shifter 13, which 115 enables the spring 11 to throw the clutch member 10 into clutching engagement with the hub of the spur gear 8. A set of nails has previously been delivered in the manner described to the slide 51, and this is 120 moved forwardly underneath the drivers 23 by a movement of the lever 75. The throwing of the clutch as above described starts the machine in motion, and the drivers descend and drive all the nails simultaneously. 125 As soon as the operator releases the clutch-shifting rod 14, it is immediately returned into engagement with the groove of the clutch member, and the cam wall 12 thereof engages said rod to thereby automatically 130

disengage the clutch as soon as the gear wheel 8 has made one complete revolution. The movement of the eccentric has in the meanwhile actuated the described connection to tilt the nail receptacle 38, so that another set of nails will have been delivered to the nail tubes in the manner before described.

In order to effect the endwise reciprocation of the bar 46, I provide the frame with the cam lugs 77 (see Figs. 1, 3, 10 and 11) at opposite ends of the said bar, one of these lugs having the cam surface 78, and the other the cam surface 79. As the hopper is tilted downwardly and forwardly, carrying with it the bar 46, one end of this bar will be engaged with the cam surface 78, thereby moving the bar endwise to nail-releasing position. Upon the reverse tilting movement of the hopper, the cam surface 79 will engage the opposite end of the bar 46 to move it to its original position. It will be understood that the counterweight 72 will act to automatically return the nail carrier 51 to its receiving position as soon as the lever 75 is released.

In Fig. 1^a I have shown one of the completed brooms as finished by my machine. The cap A and the band a are shown as formed from a single piece of metal, with the integral connection b. The end or press heads press this cap and band securely in place upon the broom, and the cap and band are nailed simultaneously. The nails which secure the handle in the broom are also driven simultaneously with the other nails. The driving head 21, the top anvil press plate 24, and the nail carrier slide 51 are made removable so that different parts may be used interchangeably for making different sizes of brooms.

My invention provides a simple and effi-

cient machine by which the operations of pressing and nailing brooms may be rapidly, accurately and economically performed. 45

It will be understood that the machine as herein shown and described may be changed in various ways. Thus, the driving gearing, the clutch, the various actuating connections, the details of the nail-assorting and feeding devices may be widely changed, and various other changes may be made within the scope of the appended claim. 50

I claim:—

In a machine for forming and nailing brooms, the combination of a pair of shaping heads having their opposing faces formed to simultaneously and completely shape both laterally and vertically a broom and also a metal cap or band applied thereto, the upper of said heads being fixed and the lower one being movable, and the upper having a series of vertical nail apertures therethrough, a nail driver head mounted for vertical reciprocation above the upper 65 head and having a plurality of driving members in line with said apertures, said driver head being fixed against movement except in a vertical direction, and a nail carrier mounted to reciprocate into and out 70 of a position between the upper head and the nail driver head, and having a plurality of nail seats arranged to be brought into register with the driving members and the said apertures, together with actuating 75 gear and connections for the nail driver head and the nail carrier; substantially as described.

In testimony whereof, I have hereunto set my hand.

WALTER S. LANG.
